UNITED STATES PATENT OFFICE.

LEO WALLENSTEIN, OF BROOKLYN, AND SAMUEL WALLENSTEIN, OF NEW YORK, N. Y.

LOOSE-LEAF BINDER.

Application filed March 12, 1921. Serial No. 451,794.

To all whom it may concern:

Be it known that we, LEO WALLENSTEIN, a citizen of the United States, residing at Brooklyn, in the county of Kings and State 5 of New York, and SAMUEL WALLENSTEIN, a citizen of the United States, residing at the Bronx, in the county of Bronx and State of New York, have invented certain new and useful Improvements in Loose-
10 Leaf Binders, of which the following is a specification.

This invention relates to loose leaf binders and has for one object to provide a binder adjustable for different sized per-
15 forated sheets or for sheets having per-
forations different distances apart or dif-
ferently located therein.

The loose leaf binders ordinarily in use have the great disadvantage, that the posts 20 which hold the leaves are usually secured against longitudinal displacement on the binder member, and could be used only for perforations a certain distance apart. This is a great disadvantage and makes it im-
25 possible to use similar binders with per-
forated sheets of different sizes and hav-
ing the holes different spaces apart.

The present invention overcomes these disadvantages.

Another object of the invention is to pro-
30 vide a binder as above described in which all the binder posts of one binder member may be locked by a single movement.

Another object of the invention is to pro-
35 vide an economically manufactured, easily operated sectional binder post, the sections of which may very quickly be assembled and disassembled for adjusting the length of the posts for different numbers of leaves.

40 The loose leaf binder posts hitherto em-
ployed, which are adjustable in length have the great disadvantage, that the posts are usually rigidly secured together by threaded connections. Such fittings are costly and
45 require a long time to manipulate.

The present invention overcomes this dis-
advantage.

Other objects of the invention will ap-
50 pear as the description proceeds; and while herein minute details of the invention are

described, the invention is not limited to these, since many and various changes may be made without departing from the scope of the invention as claimed.

In the accompanying drawing showing by 55 way of example several of many possible embodiments of the invention,

Fig. 1 is a perspective view of our im-
proved binder;

Fig. 2 is a longitudinal section of the 60 upper binder member;

Fig. 3 is a cross section of the binder with the covers broken away;

Fig. 4 is a longitudinal section of a modi-
fied form of lower binder member; 65

Fig. 5 is a cross section similar to Fig. 3, of a binder embodying the member of Fig. 4;

Fig. 6 is a side elevation partly in longi-
tudinal section of a form of binder post; 70

Fig. 7 is an enlarged fragmental section of the same; and;

Fig. 8 is a side elevation of the post.

The form of our improved loose leaf binder shown in Figs. 1, 2 and 3, com- 75
prises an upper binder member 10 (Fig. 1), a lower binder member 11 and cover boards 12 hingedly secured to said members 10 and 11 respectively. Loose leaves 15 (Fig. 3) are disposed between said members 10 and 11 respectively and the associated cover boards and provided with perforations 16 or notches at the inner edge portion. Blocks 17 and 18 slidable in said members 10 and 11 respectively are provided with openings 19 and 20 adapted, when the blocks are slid, to register with certain of said perforations 16 or notches and to receive posts 22 disposed in said openings 19 and 20 and perforations 16 or notches and secured in 90 the openings.

The upper binder member 10 comprises upper and lower parallel spaced walls 23 and 24 respectively provided with register-
ing post-receiving slots 25 (Fig. 1) extend- 95
ing longitudinally of the member. The lock-
ing blocks 17 slidable therein are each pro-
vided with a longitudinal rod-receiving bore 26 approximately tangentially intersected by said locking bore. Bearing blocks 28 in 100

opposite ends of said binder member are provided with alined bearing apertures 29 disposed longitudinally of the binder member and receiving a locking rod 30 rotatable in said bearing apertures and having a squared key-receiving end 31 and having its intermediate part disposed in said bores and provided with a flat side 33.

The lower binder member 11 of Figs. 1 and 3, comprises upper and lower parallel spaced walls the upper wall only being provided with post-receiving slots 35 (Fig. 3) extending longitudinally of the member. The locking blocks 18 are also each provided with a longitudinal rod-receiving bore 36 and at its middle part with the vertical post-receiving locking opening 20 approximately tangentially intersecting with rod-receiving bore and approximately registering with said slots 36 but slightly smaller in diameter than said first-named locking openings 19. Said lower member also carries bearing blocks 28 in opposite ends thereof provided with alined bearing apertures disposed longitudinally of the binder member similar to the bearing apertures 29. A locking rod 40 (Fig. 3) rotatable in said bearing apertures has a squared key-receiving end 31 (Fig. 1) and has its intermediate part engaging in said bores and provided with a flat side 43 similar to the flat side 33.

The posts 22 disposed in said retaining openings 19 and 20 pass through said slots and locking openings and are substantially disengaged from said locking rods when the flat sides 33 and 43 are turned toward the posts, but when the flat side is turned away from the posts, the round side of the lower locking rod 40 engages the post shanks 44 secured to or associated with the blocks 18 in any suitable manner such as being riveted in the opening 20 and holds the blocks 18 against longitudinal displacement, while the upper rod 30 when turned with the round side to the post locks the post in the opening 19 and also holds the upper block 17 against longitudinal displacement.

While any form of binding post may be used, a sectional binding post as shown in Figs. 6 to 8 is preferred. This post consists of a lower section 45, having shanks 44 and 46, and one or more upper sections 47, each, except the top section, having a reduced shank similar to the shank 46 and having at its bottom end a shank-receiving bore 48 having at its inner end a small aperture extension 49. Said bore forms side walls 50 provided on opposite sides with bayonet slots 52 each turned in the same direction for forming undercut recesses having backwardly disposed recessed seats 54 on diametrically opposite sides of said wall. A diametric pin 55 in the shank 46 has both ends projecting and adapted to pass through said bayonet slots 52 of an adjacent section

and to rest in said seats 54. A helical spring 56 in the bottom of each bore 48 has an axial extension 57 fitted tightly in said extension 49, said spring being compressible by the shank 46 in said bore and yieldably pressing on the shank to hold said projecting ends of the pin in said seats.

With the same upper binder member 10 we may use either the lower binder member 11 or 11^a (Figs. 4 and 5).

The lower binder member 11^a is similar to the binder member 11, comprising upper and lower parallel spaced walls, the upper wall only being provided with post-receiving slots 35. The retaining blocks 58 slidably disposed in said lower binder member are each provided with a vertical post-receiving opening 60 spaced from a threaded longitudinal rod-receiving bore 66 and approximately registering with said respective slots 35. Bearing blocks 28 in opposite ends of said binder member are provided with alined bearing apertures 29 disposed longitudinally of the binder member. An intermediately threaded adjusting rod 70 having a squared key-receiving end 71, and smooth end portions 72 engaged in said apertures 29, has intermediate right and left threads 73 engaging in said threaded bores 66. The posts 75 are secured to or associated with the blocks 58 such as by being riveted in said openings 60 and pass through said slots 35 and locking openings 19 and are locked by said locking rod 30 as explained. The rod 70 does not engage the posts; but rotation of the rod 70 moves the blocks 58 in opposite directions, and thus spaces them different distances apart. Fig. 5 shows a binding post 75 having a threaded connection 76 for an extension section; it is understood that either form of post section 75 or 45 may be used with either binder member.

The operation of the device is very simple. The blocks 18 with their posts, being unlocked by turning the flat side 43 to the shank 44, are slid to receive the desired perforations of the sheet. The sheet is then moved to the desired location of the binder and the blocks 18 locked by rotation of the rod 40 with a key. The blocks 17 are then in like manner unlocked and placed upon the posts and the upper member moved endwise to be flush with the lower member, whereupon the rod 30 is rotated to the position of Fig. 3 to lock the upper blocks 18.

Obviously, if many leaves are to be received in the binder, additional sections 47 must be added to the post sections 45, which is done merely by placing the bore 48 upon the shank 46 and passing the ends of the pin 55 through the slots 52 to the seats 54.

If sets of small leaves are to be used in the same plane with the upper edge of one adjacent to the lower edge of the other, ad-

ditional posts 22 and blocks 17 and 18 will be required in order that each set of leaves may have two posts.

By the use of three posts and sheets 5 shorter than the binder members, the sheets may be off-set in the well known manner of ledger posting.

With the device of Figs. 4 and 5, the blocks 58 and their posts are adjusted to receive the required perforations of the leaves by rotating the rod 70, but in this case the posts each are thereby arranged equal distance from the mid point of the binder member 11^a. In this case, the upper binder member is applied and locked as above described.

Having thus described our invention, we claim:

1. In combination, a pair of binder members; a pair of blocks longitudinally adjustable on each of said members; removable posts connecting corresponding blocks of the respective members; and unitary means for locking the posts respectively to both blocks of one member.

2. In combination, a pair of binder members; blocks longitudinally adjustable on each of said members; posts passing through and connecting corresponding blocks of the respective members; a rotary rod passing through both blocks of one of the members and adapted on rotation to lock the posts therein; and means for holding the posts in the blocks of the other member.

3. In combination, a binder member; blocks longitudinally adjustable thereon; posts received respectively by said blocks; and a rod having a flat side passing through both of said blocks and adapted on rotation to lock the posts.

4. In combination, a pair of binder members; a pair of locking blocks slidably disposed on one of said binder members and each provided with a longitudinal rod-receiving bore and at its middle part a vertical post-receiving opening; posts in said openings; a locking rod rotatable in said bores and engageable with said posts; and means connecting the posts to the other member.

5. A hollow binder member provided with a longitudinal post-receiving slot; locking blocks disposed in said binder member and each provided with a longitudinal rod-receiving bore and at its middle part a vertical post-receiving opening approximately tangentially intersecting with the rod-receiving bore; a cam formed rod rotatable in said bores; and posts disposed in said receiving openings, and passing through said slots.

6. A binder member comprising upper and lower parallel spaced walls the upper wall being provided with post-receiving slots extending longitudinally of the mem-

ber; a pair of locking blocks slidably disposed in said binder member and each provided with a longitudinal rod-receiving bore and at its middle part a vertical post-receiving locking opening approximately tangentially intersecting with said rod-receiving bore and approximately registering with said slots; bearing blocks in opposite ends of said binder member provided with alined bearing apertures disposed longitudinally of the binder member; a locking rod rotatable in said bearing apertures and having a squared key receiving end and having its intermediate part engaging in said bores and provided with a flat side; and posts disposed in said receiving openings, and passing through said slots and substantially disengaged from said locking rods when the flat side is turned toward the posts, and adapted to be locked by said locking rods when the flat side is turned away from the post.

7. In combination, in a loose leaf binder, an upper binder member comprising upper and lower parallel spaced walls respectively provided with registering post-receiving slots extending longitudinally of the member; a pair of locking blocks slidably disposed in said upper binder member and each provided with a longitudinal rod-receiving bore and at its middle part with a vertical locking opening approximately tangentially intersecting said rod-receiving bore and approximately registering with said slots; bearing blocks in opposite ends of said binder member provided with alined bearing apertures disposed longitudinally of the binder member; a locking rod rotatable in said bearing apertures and having a squared key receiving end and having its intermediate part engaging in said bores and provided with a flat side; a lower binder member; and posts adjustably secured to said lower member and passing through said slots and locking openings and substantially disengaged from said locking rod when said flat side is turned toward the post, and adapted to be locked by said locking rod when the flat side is turned away from the post.

8. A hollow binder member comprising upper and lower parallel spaced walls, the upper wall being provided with post-receiving slots extending longitudinally of the member; a pair of retaining blocks slidably disposed in said binder member and each provided with a threaded longitudinal rod-receiving bore and at its middle part with a vertical post-receiving opening spaced from said rod-receiving bore and approximately registering with said respective slots; bearing blocks in opposite ends of said binder member provided with alined bearing apertures disposed longitudinally of the binder member; an intermediate threaded

- adjusting rod having a squared key-receiving end, smooth end portions in said apertures, and intermediate right and left threads engaging in said threaded bores; 5 and posts secured in said retaining openings and passing through said slots.
9. In combination, in a loose leaf binder, an upper binder member; a lower binder member; loose leaves disposed between said 10 members respectively; blocks slideable on said members respectively; and posts secured to corresponding blocks of the respective members.
10. In combination, in a loose leaf binder; an upper binder member; a lower binder member; loose leaves disposed between said members respectively and provided with perforations; blocks slideable in said members respectively and provided with 15 openings adapted, when the blocks are slid, to register with certain of said perforations or notches; and connecting members disposed in said openings and perforations and secured in said openings.
11. In combination, in a loose leaf binder; an upper binder member; a lower binder member; cover boards hingedly secured to said members respectively; loose leaves disposed between said members respectively 20 and the associated cover boards and provided with perforations or notches at the inner edge portion; blocks slideable in said members respectively and provided with openings, adapted when the blocks are slid, to register with certain of said perforations or notches; posts disposed in said 25 openings and perforations or notches and fast in said openings of the blocks of one member; and means for releasably securing the posts in the blocks of the other member.
12. In combination, a plurality of sections one having a reduced shank and one having a bore forming side walls provided 30 on opposite sides with bayonet slots each turned in the same direction and forming recesses having backwardly disposed recessed seats; a pin in said shank having its ends projecting and adapted to pass through 35 said bayonet slots and to rest in said seats; and a spring in the bottom of said bore and adapted to press on the shank to hold said 40 projecting ends in said seats.
13. In combination, a plurality of post sections one having a reduced shank and one having a bore having in its inner end a small extension, said bore forming side walls provided on opposite sides with bayonet 45 slots forming backwardly disposed seats; a transverse pin in said shank having its ends projecting and adapted to rest in said seats; and a spring in said bore and having an axial extension fitted tightly in 50 said extension bore, said spring adapted to 55 hold said projecting ends in said seats.
14. In combination, in a sectional binding post; a plurality of sections one having a shank and one having a shank-receiving bore having at its inner end a small aperture extension, said bore forming side walls 60 provided on opposite sides with bayonet slots each turned in the same direction and forming recesses having backwardly disposed recessed seats on diametrically opposite sides of said wall; a diametric pin in 65 the shank having both ends projecting and adapted to pass through said bayonet slots of the adjacent section and to rest in said seats; and a helical spring in the bottom of said bore and having an axial extension 70 fitted tightly in said extension bore, said spring being compressible by the shank in the bore and adapted yieldably to press on the shank to hold said projecting ends in 75 said seats.
15. In combination, a binder member; a block adjustable thereon; a post received by said block; and a unitary means adapted to lock the post in the block and the block 80 in adjusted position.
16. In combination, a binder member having longitudinally extending openings in the side thereof; means slidably movable in the binder member having transverse bores; posts received in said bores and extending through said openings; and means cooperating between the binder member and said 85 slidably means and engageable with the posts for exerting pressure on a side portion of the posts for maintaining the posts and slidable means stationary in the binder member and the posts spaced apart in 90 said openings.
17. In combination, a binder member having longitudinally extending openings in the side thereof; means slidably movable in the binder member having transverse bores; posts received in said bores and extending through said openings; and means 95 operable from an end of the binder member cooperating between the binder member and said slidably means and engageable with the posts, for exerting pressure on a side portion of the posts for maintaining the posts and slidable means stationary in the binder member and the posts spaced apart in 100 said openings.
18. In combination, a binder member having longitudinal openings in the side thereof; blocks slidably movable in the binder member having transverse bores; posts received in said bores and extending through said openings; and means cooperating between the binder member and said 105 blocks and engageable with the posts for exerting pressure on a side portion of the posts for maintaining the posts and blocks stationary in the binder member and the posts spaced apart in 110 said openings.
19. In combination, a binder member 115

- having longitudinally extending openings in the side thereof; blocks slidably movable in the binder member having transverse bores; posts received in said bores and extending through said openings; and means operable from an end of the binder member cooperating between the binder member and said slideable block and engageable with the posts for exerting pressure on a side portion of the posts for maintaining the posts and slideable blocks stationary in the binder member and the posts spaced apart in said openings.
20. In a binder member, a pair of blocks longitudinally adjustable on said member; posts removable from the blocks; and a single rod on the member for locking the blocks and posts against movement.
21. In combination, a binder member; a connecting member adjustably movable on said member; and a rod eccentric from end to end passing through said binder member and adapted on rotation to lock the connecting member to the binder member.
22. In combination, a binder member; a post thereon; and a rod passing through said member and having a cylindrical side and a flat side extending throughout the rod, the cylindrical side being adapted on rotation of the rod to lock the post in adjusted position on the member.
23. In combination, a binder member; a block longitudinally adjustable thereon; a post received by said block; and means for detachably locking the post in the block.
24. In combination, a binder member, a post longitudinally adjustable on said member; a flattened cylindrical rotatable rod on the member; and means independent of the binder member for holding the rod against the post when the rod is rotated to locking position.
25. In a binder member, a post on said member; a rod on the member for locking the post; and means independent of the binder member for holding said rod and post against movement apart while locked.
26. In combination, a binder member; blocks movable longitudinally thereon; a post received by each block; and a rod having a flat side and a cylindrical side and passing through said blocks and adapted on rotation to lock the posts and blocks in longitudinally adjusted position.
27. In a binder member, blocks on said member; removable posts received in the blocks; and a single locking rod on the member movable to position for locking the post and held by said block against movement away from the post.
28. In combination, a pair of binder members; blocks movable on said members respectively; posts associated with the blocks of one member and secured to the blocks of
- the other member; means to lock the associated blocks to the posts; and means for holding the other blocks spaced apart.
29. In combination, a pair of binder members; retaining blocks and locking blocks slideable on said members respectively; posts associated with the locking blocks and secured to the retaining blocks; means for locking the locking blocks to the associated posts, and means for adjustably holding the retaining blocks on their member.
30. In combination, a pair of binder members; leaves disposed between said members; retaining blocks and locking blocks slideable on said members respectively; posts associated with the locking blocks and secured to the retaining blocks; a cam-formed eccentric rod passing through the locking blocks and adapted on rotation to lock the blocks to the associated posts; and an adjusting rod having intermediate right and left threads engaging the retaining blocks.
31. In a binder, the combination with upper and lower hollow members, of a plurality of blocks in the lower member and slideable therein, threaded bores in said blocks, means in said lower member cooperating with said threaded bores for adjustably moving the blocks longitudinally, there being openings in the upper part of said lower member, posts associated with said blocks and movable in said openings, longitudinally movable blocks in the upper member, there being apertures in said latter blocks for cooperating with the posts slideable in the lower member, and means coacting with the blocks in the upper member for locking the posts thereto.
32. In a binder, the combination with upper lower hollow members, of a plurality of blocks in each member, said blocks being longitudinally slideable therein, posts associated with the blocks in the lower member, there being apertures in the blocks of the upper members cooperating with said posts, and means in the upper member for locking the posts in the apertures.
33. In a binder, the combination with upper and lower hollow members, of a plurality of blocks longitudinally movable in said lower member, there being threaded bores in said blocks, means in said lower member cooperating with said bores for positioning said blocks, posts associated with said blocks, a plurality of blocks movable in said upper hollow member, there being openings in said latter blocks for receiving the posts therein, and means extending into said openings for locking the posts therein.

LEO WALLENSTEIN,
SAMUEL WALLENSTEIN.
